(57) **CLAIM**

The ornamental design for water-pump pliers handles, as shown and described.

DESCRIPTION

FIG. 1 is a perspective view of water-pump pliers handles showing my new design;

FIG. 2 is a front elevational view thereof;

FIG. 3 is a side elevational view thereof;

FIG. 4 is a rear elevational view thereof;

FIG. 5 is a side elevational view thereof, from the side opposite the view in FIG. 3;

FIG. 6 is a bottom plan view thereof; and,

FIG. 7 is a top plan view thereof.

The characteristic feature of the design resides in the presence of areas of contrasting colors or shading on the handles as shown in the drawings.

The shanks, joint and jaws of the pliers shown in broken lines in the drawing are exemplary environmental structure and form no part of the design to be patented.
